UNITED STATES PATENT OFFICE.

HENRY SECCO, OF NEW YORK, N. Y., ASSIGNOR OF ONE-THIRD TO SAMUEL F. SNIFFEN, OF SAME PLACE.

CARRIAGE OR WAGON JACK.

SPECIFICATION forming part of Letters Patent No. 360,116, dated March 29, 1887.

Application filed January 3, 1887. Serial No. 223,169. (No model.)

To all whom it may concern:

Be it known that I, HENRY SECCO, a citizen of the Republic of France, and a resident of New York city, in the county of New York 5 and State of New York, have invented certain new and useful Improvements in Carriage or Wagon Jacks, of which the following is a specification.

Previous to my invention numerous contrivances have been devised for lifting the axles of conveyances for the purpose of removing the wheels or washing the same; but to all such contrivances, so far as my knowledge extends, there has existed some objection, either as to 15 construction or mode of operation.

My invention has for its main objects to produce a carriage or wagon jack which shall be simple of construction, easy and speedy of operation, and capable of performing all the 20 functions required by those having occasion to use such contrivances.

To these ends and objects my invention consists in the various features of construction and combinations of parts, hereinafter more 25 fully explained, and particularly pointed out in the claims of this specification.

In the accompanying drawings, Figure 1 is a side elevation, partly in section, of a contrivance embodying my invention. Fig. 2 is a detail view of the lifting bar or frame detached. Fig. 3 is a horizontal section taken at the line *x x* of Fig. 1. Fig. 4 is an enlarged perspective view of the upper portion of the jack. Fig. 5 is a horizontal section taken at the line *y y* 35 of Fig. 1, and Fig. 6 is a perspective view of the adjustable block or support detached.

In the several views the same parts will be found designated by the same letters and numerals of reference.

A is a post or standard, preferably of wood, and enlarged at its lower end to form feet *a a*, to which are bolted at *b b*, on each side thereof and at right angles thereto, two additional feet, *c c*, thus providing a substantial base for the 40 structure. The post or standard is slotted longitudinally at 1 and 2, and face-plates 3 and 4 are secured to the post at opposite sides, as shown.

About centrally of the length of the post a 45 cut-out or opening is made for the reception of the toothed end *e* of the lever B, which, as

shown, is fulcrumed in said post by a pin or bolt, 5, passing therethrough and through a hole in the lever and secured by nuts or heads 6, washers 7 being introduced between the 55 nuts or heads and the sides of the post, as illustrated.

C is the lifting bar or frame, constructed to slide vertically in front of the post A. At two points, preferably, the lifting-bar is provided with perforated lugs or ears 8 8, which are fitted to slide in the slotted front of the post, and are held in place by bolts or pins 9 passing through the slots 1 and 2 and the eyes in the lugs or ears 8 8. Nuts 10 retain the 65 bolts 9 in place.

The lifting bar or frame, made preferably of metal, is composed, essentially, of a back bar, 11, and an inclined front bar, 12, in addition to the perforated lugs above mentioned. The 70 back bar is provided with two racks, 13 and 14, and the front bar with a row of upwardly-inclined teeth 15. At the upper end of the lifting-bar is provided a seat, 16, for supporting the axles of high vehicles. At 17 the lifting-bar is perforated, so that cheek-pieces 18, 75 preferably of wood, may be secured on each side thereof by bolts or rivets 19.

D is a detachable adjustable axle-support, preferably of metal, consisting, essentially, of 80 an axle seat or bearing, 20, and a bar or plate, 21, provided with downwardly-inclined teeth or lugs 22, to fit into the spaces between the teeth 15 on the front bar of the lifting-frame. A plate or brace, 23, extends from the lower 85 portion of the bar 21 to the under side of the forward end of the axle-bearing 20, and greatly strengthens the contrivance. This brace 23 also forms a handle for facilitating in adjusting the block. The forward end of the axle-bearing 20 is cut out or notched, as at 24, for the purpose of straddling the "reach," when the jack is to be used in connection with a vehicle having such a device.

At the upper end of the post A is pivoted, 95 at 25, a lever catch or pawl, 26, which engages with the teeth 14 on the back bar, 11, and which is provided with a handle portion or extension, 27, projecting back of the post or standard. To an ear, 28, cast on this extension, is 100 attached one end of a chain, 29, the other end of which is fastened to a foot-lever, 30, piv-

oted at 31 in the post. The free end of a curved bar-spring, 32, rests against the under side of the handle portion 27 of the catch 26, and serves to keep the latter in engagement with the teeth 14 during the raising of the lifting-bar. The metallic face-plates 3 and 4 are provided with flanges 33, which form a lining for the wearing sides of the slots 1 and 2, and these plates are also provided with perforated extensions 34 and 35, to form washers for the heads and nuts of the pivots of the levers 26 and 30. 36 is a handle for carrying the jack about.

When the parts have been assembled together, as in Fig. 1, the contrivance is ready for operation. The block or support D being placed beneath the axle of the vehicle, the outer end of the lever B is depressed, causing the teeth of the inner portion, e, to move upwardly, and these teeth being always in engagement with the teeth 13 on the back bar, 11, operate to elevate the lifting-frame C and raise the wheels of the vehicle from the ground.

25 During the elevation of the lifting-frame the pawl or catch 26 moves in and out between the teeth 14 on the bar 11, and when the depression of the lever B has ceased the pawl will remain in engagement with said teeth and prevent the descent of the lifting-frame.

If the vehicle operated upon be a light one and not raised very high, it may be lowered without straining or injury by pressing the foot upon the lever 30, and through the connection 29 disengaging the pawl 26 from the rack 14, thus allowing the weight of the vehicle to push down the lifting-bar; but if the vehicle be a heavy one, or raised quite high, it is better to keep the hand upon the lever B and 40 let the lifting-bar come down slowly.

If found desirable, the foot-lever may be dispensed with and the pawl 26 disengaged by depressing the extension 27; but I prefer to have both present in the contrivance. When 45 the pawl 26 is used alone, the lever B should be moved slightly downward and made to bear the weight of the vehicle, in order to start the disengagement of the pawl, after which the latter may be easily held disengaged while the 50 lifting-bar and vehicle are descending.

One important advantage in the use of my contrivance is that during all the time the vehicle is held raised the lifting-bar, which sup-

ports it, is held up by the pawl 26, and that during the descent of the vehicle the lever B 55 is in engagement with the lifting-bar, and the operator thus is given such perfect control over the same that he may let the heaviest vehicle down until the wheels touch the ground without giving it the slightest shock or jar. 60

By the employment of the detachable support or block D, I am enabled to save time in the lifting of the axles, and also enabled to raise axles of any height, the block being simply shifted higher or lower, according to the 65 height of the axle, as will be apparent from an inspection of the accompanying drawings.

By reason of the presence of the foot-pieces a and c, the contrivance possesses great stability, and I have been enabled to place the 70 same in the center of the axle and raise both wheels from the floor at one time; and by reason of the strength of the structure and the arrangements of its parts and the mode of operation thereof, I have been able to lift both 75 wheels of one of the heaviest steam fire-engines and lower them again with the greatest ease and without giving any shock whatever to the engine.

What I claim as new, and desire to secure by 80 Letters Patent, is—

1. The combination of the post, the lifting-bar provided with the racks 13 and 14 and the toothed bar 15, the lever B, the pawl 26, and the adjustable support D. 85

2. The combination of the post, the lifting-bar provided with the racks 13 and 14, the lever B, the pawl 26, the foot-lever 30, and a connection, as 29, between the pawl and the foot-lever. 90

3. The combination of the post slotted in front and having the slots 1 and 2, the lifting-bar having the perforated lugs 8 8 and the racks 13 and 14, the pins 9 9, the lever B, and the pawl 26. 95

4. The combination of the post, the lifting-bar provided with the racks 13 and 14, the lever B, the pawl 26, and the adjustable support D, having the cut-out 24.

Signed at New York, in the county of New York and State of New York, this 18th day of December, A. D. 1886.

HENRY SECCO.
